UNITED STATES PATENT OFFICE.

JOHN H. BRASSELL, OF LOS ANGELES, CALIFORNIA.

WIRE LOOPING AND COILING TOOL.

1,413,453.

Specification of Letters Patent. Patented Apr. 18, 1922.

Application filed April 12, 1921. Serial No. 460,645.

To all whom it may concern:

Be it known that I, JOHN H. BRASSELL, a citizen of the United States, residing at Los Angeles, in the county of Los Angeles 5 and State of California, have invented new and useful Improvements in Wire Looping and Coiling Tools, of which the following is a specification.

This invention relates to tools and has 10 particular reference to a wire looping and coiling tool.

One object of this invention is to provide a tool of the character described, which is equipped with changeable adjustable jaws 15 for operative use on various sizes of cables.

Other objects of the invention are to provide means associated with the handles of the tools for retaining the jaws in a fixed position, and means disposed between the 20 jaws adapted to support and place in an operative position the wire to be coiled.

A further object of the invention is to provide a tool of the character described, which is simple in construction, compact in 25 the arrangement of its parts, economical to manufacture, and highly serviceable.

Other objects and advantages will be apparent during the course of the following description.

30. In the accompanying drawings forming a part of this specification and in which like numerals are employed to designate like parts throughout the same,

Figure 1 is a side elevation of my improved tool,

Figure 2 is a sectional view of the supporting element, and

Figure 3 is a detail view of one of the jaws.

40. In the accompanying drawings wherein for the purpose of illustration is shown a preferred embodiment of my invention, the numerals 4 and 5 indicate a pair of jaws respectively, mounted to swing upon a pivot 45 pin 6 and having handle 7 and 8 respectively, the handle 7 extending from and being integrally formed with the jaw 5, while the handle 8 extends from and is integrally formed with the jaw 4. For the 50 purpose of retaining the handles in pivotal relation, a nut 9 encircles the pivot pin 6.

Pivots connected at 10 to the handle 8 is one extremity of a curved arm 11, having its lower face partly serrated as at 12 55 and adapted to have acute movement in a slot 13 formed in the handle 7. Secured

to the outer edge of the handle 7, is a pawl 14 which contacts with a serrated face 12, being actuated by a single leaf spring 15 riveted to the handle 7. This spring acting 60 in conjunction with the pawl serves to automatically lock the curved arm in a fixed position, the purpose of which will be hereinafter described.

Pivots mounted on the inner face of 65 the jaws 4 and 5 adjacent the point of pivotal connection, are toggle levers 16 and 17, which are in turn connected to a supporting element 18. This element has provided therein an arcuate groove 19, as shown 70 to advantage in Figure 2, which is adapted to retain therein the wire to be coiled. It will be apparent that inward movement of the jaws will cause the element 18 to travel in a vertical direction, as indicated by the 75 arrow, and that outward movement of the jaws will cause the toggle levers to spread outwardly and lower the element 18. From the construction, it will be apparent that wire to be coiled will be placed into position 80 to be operated upon by the extremities of the jaws 5 and 6, which position is regulated by the inward and outward pressure exerted on the handles 7 and 8.

For the purpose of making the jaws 85 changeable and accordingly adjustable to various sizes of cables, I have equipped the jaws with longitudinal grooved portions 20 and 21, receivable within slots 23 provided in the jaws, and secured therein by fastening elements, preferably set screws, 24.

In the use of my device, a cable or wire is inserted in the arcuate groove of the supporting member and inward pressure on the handles 7 and 8 will cause the toggle levers 95 16 and 17 to accordingly raise the supporting element. When this action occurs the adjustable jaws will cause the strands of wire or cable to be compressed thereby forming a loop in the cable, and a twisting movement imparted to the handles will cause one of the strands to be coiled about the stationary strand. The pawl 14 actuated by the spring 15 controls the position of the curved arm and thus tends to retain the jaws 4 and 100 5 in a fixed position.

Although my tool is preferably used as a device for forming loops and coiling a strand or plurality of strands of wire about a stationary strand, nevertheless it is to be 110 understood that the tool has various other uses and it is further to be understood that

various changes in the shape, size and arrangement of parts may be resorted to without departing from the spirit of the invention or the scope of the subjoined 5 claim.

Having thus described my invention, I claim:—

A tool of the character described comprising a pair of pivoted adjustable jaws 10 and handles outwardly extending therefrom, a grooved element disposed between said jaws for holding and retaining therein wire

to be coiled, toggle levers connected to said jaws adjacent their point of pivotal contact and adapted to support said grooved element, a curved serrated arm connecting said handles, a pawl secured to one of said handles and adapted to connect with said curved arm, and tension means connected to said last mentioned handle whereby the pawl is 20 retained in a fixed position.

In testimony whereof I affix my signature.

JOHN H. BRASSELL.
